Primary Examiner — George D. Kirschbaum*Assistant Examiner* — Lillian Windham(74) *Attorney, Agent, or Firm* — Saidman DesignLaw Group, LLC(57) **CLAIM**

The ornamental design for a sensor, as shown and described.

DESCRIPTION

FIG. 1 is a front perspective view of a sensor showing our new design;
 FIG. 2 is a rear perspective view thereof;

FIG. 3 is a front view thereof;

FIG. 4 is a rear view thereof;

FIG. 5 is a left side view thereof, the right side view being a mirror image;

FIG. 6 is a top view thereof; and,

FIG. 7 is a bottom view thereof.

The broken lines illustrate portions of the sensor which form no part of the claimed design.
